UNITED STATES PATENT OFFICE

HUGH P. ROBBINS, OF CHICAGO, ILLINOIS

INTERMEDIATE CANE CARRIER

Application filed July 26, 1927. Serial No. 208,551.

This invention relates to intermediate cane carriers which carry the bagasse from one set of crusher rolls to another in sugar cane crushing operations.

5 Heretofore the bagasse conveyors have been carried by big bulky chains driven by sprockets connected to the driving roller, and in most instances three of such chains have been employed. These chains have been 10 positioned between the sides of the conveyor frame and connected at suitable intervals to the aprons. Idlers have been positioned at intervals to support the return chains which swing down in long sweeping arcs and sometimes 15 only one set of idlers have been used to support the chains of a long conveyor. This type of chain drive has produced what is referred to in the art as a "nut-cracker" which results from the action of loose chains 20 and the tendency of the links to fold or double upon themselves. The wear and tear, strains and stresses resulting from this construction has been the cause of much damage to the conveyors which is increased if the 25 overlapping portions of the aprons become bent or twisted. It is almost impossible to get three chains to operate uniformly and evenly, due to uneven pitch of the sprockets or to stretching of the chains, or to wear, and 30 any jamming of the bagasse as it is fed to a succeeding set of rolls often causes breakage of the chains. Also, the big sweep of the return chains makes it dangerous for the clean-up man to work under the conveyor and 35 between the sets of rolls.

The object of the invention is to provide means for eliminating these defects of existing apparatus, to provide new and improved means for securing greater efficiency in the 40 operation of intermediate cane carriers, to prevent jamming of the bagasse by forcing the bagasse between the rolls, and to reduce the stresses and strains on the chains.

Another object is to provide novel means 45 to drive the conveyor by connecting the drive shaft to the intermediate shaft and providing means for adjusting this drive in accordance with the position in which the nose of the conveyor is set.

50 Another object is to provide a plurality of

rollers on the driving or nose shaft and intermediate drive or nose shaft which will interlock with aprons or pans of the conveyor and assist in driving the conveyor, and to support the aprons intermediate their ends to prevent 55 sagging.

Another object is to provide means for keeping the chains out of the juicy bagasse by attaching the chains to the outside edges of the aprons to reduce the number of chains 60 formerly required.

Another object is to provide means for supporting the top and bottom of the chain to remove all strains on the chains, to prevent the return chain from sweeping in a long 65 arc and to provide a clear space beneath the conveyor between the sets of rolls.

And a further object is to provide novel means in the assembly of the sprockets and the tail adjustment so that all danger of the 70 chains jumping a sprocket tooth is eliminated.

The accompanying drawings illustrate a selected embodiment of the invention and the views therein are as follows:

75 Fig. 1 is a side elevation of an intermediate cane carrier showing the invention applied thereto.

Fig. 2 is a detail sectional view taken transversely through the conveyor at the driving 80 end.

Fig. 3 is a detail sectional view taken on line 3—3 of Fig. 2.

Fig. 4 is a detail sectional view at the end 85 opposite to that shown in Fig. 3.

Fig. 5 is a detail sectional view taken on the line 5—5 of Fig. 2.

Fig. 6 is an end elevation showing the manner in which the apron is connected.

Fig. 7 is a detail sectional view showing the 90 manner in which the apron is connected to the chain.

Referring to the drawings 1 designates generally a set of rolls comprising the rollers 2, 3 and 4. The roller 2 is driven in any suitable manner and drives the roller 3 by means of gears 5 and 6, and the roller 4 is driven by the roller 3 through the gear 6 and 7. The roller 2 is provided with a sprocket 8 on one end thereof and drives the chain 9 which is 100

connected to the sprocket 10 to operate the conveyor.

The sprocket 10 is fixed to the nose shaft 11 suitably journaled in the frame 12 of the carrier. Parallel with the shaft 11 is a head shaft 13 which is driven by a head chain 14 on the sprockets 15 and 16. The shaft 11 and 13 are provided with sprockets 17, 17 which are mounted on each end of these shafts and drive the conveyor chains 18.

The conveyor chains are of special roller type each chain being, in fact, a double chain comprising 2 sets of links pivotally connected by pivot pins 21. A bushing 21' of less length than the pin is arranged on each pin. A roller 22 is arranged on each bushing between the outer set and the inner set of links of the chain. In the inner set of links 23, one end of one link is mounted on the pin and the adjacent end of the next link is mounted on the bushing. The pan or apron 19 is fastened to the projection 20 on the link 23 by bolts or rivets. In the outer set of links 23' the end of one link is mounted on the pin and the adjacent end of the next link is mounted on the bushing.

The pan flights travel between the fixed sides 12' which are sufficiently high to keep the blanket of bagasse from spilling or falling over the top and are positioned so that the bottom edges of the sides abut the top of the chain link, Fig. 7.

The chains 18 extend under these sides, Fig. 7, and keep the chain out of the bagasse and prevent it from coming in contact with the cane juice thereby prolonging the life of the chain and assuring better operation of the chain rollers as there is no danger of the bagasse becoming entangled or wedged in the rollers.

To prevent the bagasse or parts thereof from seeping beneath the sides where the chain extends through, I provide a strip 12" which is attached to the sides and contacts with the chain and engages the shoulders 20' formed on the links 23 as shown in Fig. 7. This strip is preferably made of wood to eliminate undue friction at this point and allows more free and unrestricted movement of the chain.

The pans are provided with high ridges 24 and deep furrows 25 so that the bagasse carried to the rolls is readily forced between the rolls and prevents jamming at that point. The ends 26 of the pans are rounded circumferentially so that the pans interlock with each other and all danger of the ends separating or cutting into each other is eliminated. This construction of the pans has a tendency to push the blanket of bagasse, especially as the bagasse enters the rollers, and practically eliminates the possibility of chokeups at this point. A plurality of rollers 27 are fixed to the shafts 11 and 13 and are adapted to engage the underside of the pans and interlock

therewith, Fig. 5, to support the pans intermediate their ends and assist in propelling the conveyor. These rollers have the same number of teeth as the sprockets 15 and 16 to synchronize the operation of the conveyor.

Heretofore, large bulky chains were necessary to drive the conveyor due to the "nut-cracking" effect on the chain and idlers and the entire weight of the chain bore directly on the idlers and sprocket. To provide a more efficient conveyor, and also to prevent the sweep of the return chain, suitable top and bottom rails 28 and 29 are provided. The entire weight of the chain is supported by the rails and prevent the "nut-cracking" effect on the chain and aprons, greatly increasing the life of the conveyor and providing protection to the operators working under the conveyor between the rollers. The chain rollers 22, Fig. 7, are provided with an annular flange 22' to guide the chain on the rails during its travel and prevent the chain slipping off the rails.

A tightener or take-up 30 is provided at the nose of the conveyor, Figs. 3 and 5 to allow adjustment of the nose relative to the rolls where the bagasse is fed to the rolls. Another tightener 31 is provided to take up the slack in the head chain 14 which connects the driving shaft 11 and the intermediate shaft 13 so that this drive may be adjusted relative to the nose. These tighteners are preferably operated by means of adjusting nuts 32 and 33 operating through members 34 and 35 permanently fixed to the frame.

To take up the slack in the conveyor chains a tightener 36, Fig. 4, is arranged at the tail of the conveyor and is adjustable to move the tail shaft 37 longitudinally relative to the conveyor. This tightener comprises an arm 38 slidably mounted on the frame and it supports one end of the tail shaft. Adjustment of the tightener is made by means of a set screw 39 threadedly mounted in the member 40 fixedly secured to the frame. A second tightener of the same construction (not shown) is likewise mounted in the frame and operates on the opposite end of the tail shaft 37 so that accurate adjustment of both conveyor chains 18 is assured.

My novel cane carrier will prevent jamming of the bagasse by forcing it between the rollers, and the heavy strains and stresses to which carriers have heretofore been subjected are reduced to a minimum. The drive causes positive operation of the carrier, and the chain parts are removed from contact with the cane juice thereby assuring longer life of the carrier. Also, the rails support the conveyor chains and prevent a drag on the conveyor and a "nut-cracking" effect on the aprons and chains.

Changes may be made in the form, construction and arrangement of parts without departing from the scope or sacrificing any

of the advantages of the invention and the right is hereby reserved to make all such changes as may fairly fall within the following claims.

5 I claim:

1. An intermediate cane carrier comprising a frame, a nose shaft and a tail shaft mounted in the frame at the ends thereof, a head shaft mounted in the frame above and behind the nose shaft, a conveyor comprising overlapping pans and side chains, sprockets at the ends of said shafts engaging said chains, power means for driving the nose shaft, a chain drive between the nose and head shafts, means for adjusting the nose shaft relative to the head and tail shafts, and independent means for adjusting the chain drive between the nose and head shafts.
2. An intermediate cane carrier comprising a frame, a nose shaft and a tail shaft mounted in the frame at the ends thereof, a head shaft mounted in the frame above and behind the nose shaft, a conveyor comprising overlapping pans and side chains, said 20 side chains each comprising an outer set of overlapping links and an inner set of overlapping links, rollers interposed between said sets of links, and pins articulating the links of said sets, the links of the inner set 25 having inwardly directed projections and the pans being secured at their ends to said projections, sprockets at the ends of said shafts engaging the rollers of said chains, and means for driving the nose shaft and the head shaft.
3. An intermediate cane carrier comprising a frame, a nose shaft and a tail shaft mounted in the frame at the ends thereof, a head shaft mounted in the frame above and behind the 30 nose shaft, a conveyor comprising overlapping pans and side chains, said side chains comprising an outer set of overlapping links and an inner set of overlapping links, rollers interposed between said sets of links, the links of the inner set 35 having inwardly directed projections and the pans being secured at their ends to said projections, shoulders on the inner links above said projections, upright sides on the frame abutting the tops of the chains, strips on said sides abutting said 40 shoulders to co-operate with the sides in retaining the material on the conveyor, sprockets at the ends of said shafts engaging the rollers of said chains, and means for driving the nose shaft and the head shaft.

HUGH P. ROBBINS.
